UNITED STATES PATENT OFFICE

ERASMIUS MANFORD BLACKSHEAR, OF BREWTON, ALABAMA

SAFETY APPLIANCE FOR AIRPLANES

Application filed February 18, 1930. Serial No. 429,362.

The invention relates to safety appliances for airplanes, and has for its object to provide a device of this character comprising a rotatable propeller located forwardly of the center of gravity of the airplane adjacent its pulling propeller and engine, and forming means whereby the operator may, by manipulating the propeller, lift the forward end of the machine when landing or taking off, or prevent the machine from going into a nose dive when in flight.

A further object is to incline the axis of the lifting propeller downwardly and forwardly for increasing its efficiency, particularly when the plane is in a downward and forwardly inclined position.

A further object is to provide a streamline hood arching the forward side of the lifting propeller and leaving the rear side open whereby it will not interfere with the action of the propeller on the air.

A further object is to provide a driving connection between the engine and the inner end of the lifting propeller shaft comprising a flexible shaft having bevel gear connections with the propeller shaft and a driven gear disposed adjacent a drive gear slidably mounted on the engine shaft and adapted to cooperate with the driven gear. Also to provide a foot pedal controlling the drive gear on the engine shaft, by means of which the operator may, at will, control the rotation of the lifting propeller.

A further object is to dispose the propeller forwardly of the center of gravity, whereby its lifting force will be adjacent the weighted forward end of the machine for obtaining maximum lifting efficiency.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a side elevation of the airplane.

Figure 2 is a bottom plan view of the forward end of the airplane.

Figure 3 is a vertical transverse sectional view taken on line 3-3 of Figure 1.

Figure 4 is a vertical longitudinal sectional view through the forward end of the airplane.

Figure 5 is a view in elevation of the slideable gear on the engine shaft.

Referring to the drawings, the numeral 1 designates the fuselage of a conventional form of airplane, 2 the wings and 3 the landing wheels. The airplane is of the puller type wherein the engine 4 is disposed adjacent the forward end of the fuselage and drives a puller propeller 5, all of which structure places the center of gravity of the machine towards the forward end thereof.

In airplanes attempts have been made to provide auxiliary lifting propellers beneath the fuselage for assisting in controlling the machine particularly when taking off, however it has been found that these propellers are located too far to the rear of the center of gravity of the machine to obtain the desired result, especially if the machine has forward momentum. To overcome this objection the lifting propeller 6 is disposed beneath the fuselage 1 forwardly of the center of gravity, and forwardly of the wings 2 where its effect will be immediately applied to the forward end of the machine for raising the nose thereof, for instance when taking off or landing, or when the machine starts into a nose spin. It will be noted that the lifting propeller 6 has its axis downwardly and forwardly inclined, therefore it will be seen that even though the airplane is in a descending inclined position said propeller will still be positioned for raising the nose of the machine, using the action of the air on the upper plane 2 for the pivotal point of movement under the influence of the propeller 6. This relation is clearly shown by the line a-a, Figure 1.

The under side of the fuselage 1 is provided with a downwardly and rearwardly inclined arcuate streamline shield 7, which 100

arches the forward side of the propeller 6 so that said propeller, when in operation may act on the air axially, and at the same time the shield 7 streamlines the device 5 when not in use. It will be noted that the rear side of the streamline shield 7 is open, thereby allowing the propeller 6 to impinge and operate on the air in the usual manner.

10 Propeller 6 is provided with an upwardly extending shaft 8, which inclines rearwardly and terminates in a bevel gear 9 within the fuselage. Extending upwardly within the fuselage are brackets 10 and 11 in bearings 12 of which the flexible shaft 13 is rotatably mounted with its ends at different angles so that the flexible shaft accommodates itself to the angular variations of its ends during the driving operation. One end 20 of the flexible shaft is provided with a bevelled gear 14, which meshes with the bevel gear 9, and the other end of the shaft, which is horizontal, is provided with a driven gear 15, with which the drive gear 25 16 is adapted to mesh upon axial movement of the drive gear 16 towards the engine 4. Drive gear 16 is slidably keyed on the engine drive shaft 17, and is controlled by the yoke 18 carried by the rearwardly extending control rod 19. Control rod 19 is slidably mounted in a bearing 20 of the bracket 10 and is normally held in rearward position by the coiled spring 21, interposed between washer 22 and the bracket 10, therefore it will be seen that under normal conditions the drive gear 16 is out of mesh with the driven gear 15, consequently the lifting propeller 6 is inoperative.

40 Pivots connected at 22^a to the rear end of push rod 19 is a connecting rod 23 which is in turn pivotally connected at 24 to a foot lever 25, which is located within easy reach of the operator's foot, and where the operator can quickly place his foot on the pedal 45 if the machine goes into a tail spin, or when taking off or landing, for operating the propeller 6 for lifting the forward end of the machine. It will be noted that when the operator moves his foot from the pedal 25 50 that the expansive action of the spring 21 will move drive gear 16 rearwardly to de-clutched position as shown in Figure 4, thereby immediately stopping the rotation of propeller 6.

55 From the above it will be seen that a lifting propeller is provided for the forward under side of an airplane adjacent the engine and propeller and forwardly of the center of gravity of the machine, and by means 60 of which propeller the operator may easily and quickly control and force the upward movement of the forward end of the machine, while landing, taking off or when in the air in case of emergency, for instance 65 when the machine starts into a nose spin.

The invention having been set forth what is claimed new and useful is:—

1. The combination with an airplane having an engine and propeller at its forward end and forwardly of its wings, of a lifting propeller carried by the underside of the airplane between the engine and wings and forwardly of the center of gravity of the airplane, driving connection between the lifting propeller and the engine, a streamline shield carried by the underside of the airplane and arching the forward side of the lifting propeller, said shield terminating rearwardly of the transverse center of the propeller. 70

2. The combination with the forward end of an airplane having an engine and propeller, of a lifting propeller beneath said forward end, a shaft carried by said propeller and extending into the airplane, a rearwardly extending flexible shaft within the airplane, said shaft having its ends rotatably mounted in bearings at different angles, gear connections between one of said shaft ends and the propeller and gear connections 80 between the other shaft end and the engine. 85

3. The combination with an airplane having an engine and propeller at the forward end of its fuselage, a lifting propeller beneath said fuselage, of a driving connection 95 between said engine and propeller, said driving connection comprising a rearwardly extending drive shaft carried by the engine, a rearwardly extending flexible shaft beneath said drive shaft within the fuselage, said flexible shaft having its ends rotatably mounted in bearings at different angles, one of said ends being parallel to the drive shaft means whereby said last named end may be driven from the engine drive shaft, the 100 other end of the flexible shaft being at a right angle to the axis of the lifting propeller and gear connections between said last named flexible shaft end and the propeller. 105

In testimony whereof he hereunto affixes 110 his signature.

ERASMIUS MANFORD BLACKSHER.
